(57) CLAIM

The ornamental design for a holder for ink pads, as shown and described.

DESCRIPTION

FIG. 1 is a top perspective view of a holder for ink pads, showing my new design;

FIG. 2 is a bottom perspective view thereof;

FIG. 3 is a top plan view thereof;

FIG. 4 is a front elevation view thereof, with a rear elevation view being a mirror image thereof.

FIG. 5 is a bottom plan view thereof; and,

FIG. 6 is a left-side elevation view thereof, with a right-side elevation view being a mirror image thereof.

The broken lines shown in the drawings depict portions of the article that form no part of the claimed design.

1 Claim, 4 Drawing Sheets(56)
